Filed Mar. 8, 1960, Ser. No. 13,498
20 Claims. (Cl. 153—2)

The present invention relates to a sheet metal forming press, and more particularly to such a press for forming both inner and outer panels for doors.

In the manufacture of doors, such as doors for mobile homes, formed of inner and outer panels flanged and connected along their edges to provide a hollow shell which may have thermal insulation or the like applied therein, and with openings cut in the panels for insertion of windows and of latches or locks, it has heretofore been a relatively slow, expensive, and tedious operation to perform the various steps necessary for so forming the panels. The press of the present invention reduces to one simple operation the several separate steps previously required, and by reason of the resulting simplification reduces the time, labor, and costs involved to a minimum. To this end, the fixed and movable parts of the press are provided with complementary die structures which in one operation of the press perform all of the bending and cutting necessary to form the panel as desired. In addition, the press incorporates in its die parts elements or members selectively and alternatively attachable in different positions so as to bend the inner and outer panels of the different respective forms thereof. Similarly, the two panels have corner portions of different shapes cut therefrom. The cutting of the several corner portions is accomplished by cooperating shearing die blocks removably secured on the press bed and platen as portions of the complementary die parts, the blocks being readily removed and replaced when the press is to operate upon an inner or outer panel after having been used to form the other panel. The arrangement is such as to permit the use of at least one of the shearing die blocks in a plurality of positions so as to cooperate in the cutting off of either square or triangular corner portions, if desired.

In the cutting of apertures, such as a window aperture, or a door lock aperture, in a panel, cooperable shearing die elements are provided on the bed and platen for preferably simultaneous cutting of all sides of the aperture. To facilitate the shearing or cutting action, and reduce the power required to cut the desired portions from the panel or sheet, at least certain of the shearing die elements have cutting edges formed with a slight curve so that the movement of the cooperating shear elements toward each other with the sheet therebetween results in a progressive cutting or shearing of the panel from the point or points at which the curved cutting edges first contact the sheet. In this connection, at least certain of the apertures must be cut in opposite portions of the two panels as they are respectively and similarly positioned in the press, since in assembly one of the panels must be reversed from its forming position in order to engage properly with the other, and registration of corresponding apertures would not occur if the apertures were not cut as explained. The invention provides easily transposable cutting means to allow the relative reversal of location of the openings.

It is accordingly an object of the invention to provide a sheet metal forming press for forming different shapes of panels assemblable to provide a hollow door construction in which either panel may be formed with equal facility, and which is adaptable with a minimum expenditure of effort and time to form either type of panel.

Another object is the provision of a panel-forming press having complementary die parts for bending edge por-

2

tions of a metal sheet into either upstanding flanges or rebent flanges, the die part including die members selectively securable in one or the other of said die parts to provide for the formation of either an upstanding flange or rebent flanges thereby.

Another object is the provision of a sheet metal forming press having complementary relatively movable die structures including shearing die block means for cutting corner portions from a sheet or panel which employ alternate sets of such means for cutting either triangular or square corner portions from the panel; and also the optional provision of shear blocks employable in either set of die block means by selective securement of such blocks in either of two positions thereof.

Another object is the provision of complementary shearing die elements in cooperating relatively movable die parts for cutting portions from a panel to provide openings therein, in which at least certain of the shearing elements are formed with curved cutting edges to facilitate the cutting of the apertures by effecting a progressive shear.

It is another object to provide readily reversible means for effecting relatively reverse formation of panels in relatively movable complementary die means.

It is also an object of the invention to provide a sheet metal forming press including novel ejector means for facilitating removal of the formed panel from the press.

Other and further objects, advantages, and features of the invention will be apparent to those skilled in the art from the following detailed description, taken in conjunction with the accompanying drawings, in which:

FIG. 1 is a front elevational view of a press according to the invention, in its open or loading position;

FIG. 2 is a fragmentary view similar to FIG. 1, but showing the press in its closed or forming position;

FIG. 3 is a horizontal sectional view taken substantially as indicated by the line 3—3 of FIG. 1, showing the movable platen of the press in plan;

FIG. 4 is a perspective view showing the two panels prior to assembly;

FIG. 5 is an enlarged fragmentary detail view in perspective of one corner-cutting die construction of the press in the open position thereof;

FIG. 6 is a view of the construction of FIG. 5 in the forming position of the press;

FIG. 7 is an enlarged plan view of the platen-mounted portion of another corner-cutting die structure;

FIG. 8 is an enlarged perspective view of another corner-cutting die construction of the press in the open position thereof;

FIG. 9 is an enlarged cross-sectional view taken substantially as indicated by the line 9—9 of FIG. 3, showing the upper and lower die parts in the open or idle position;

FIG. 10 is a view similar to FIG. 9, but showing the parts in the closed or completed forming position;

FIG. 11 is a view similar to FIG. 10, but showing the parts in a different arrangement to impart a different form to the panel; and

FIG. 12 is a fragmentary perspective view of shearing die means of the press for cutting an opening in the panel.

Referring first to FIG. 4, there are shown an inner panel I and an outer panel O which may be assembled and secured together to form a door. The panel O has upstanding flanges formed along the four edges thereof, all of substantially the same height. The flange H along one longitudinal edge of the panel which is to correspond to the hinge edge of the finished door has its ends substantially squared or perpendicular to the bend line of the flange, and the adjacent ends of the flanges F on the transverse edges of the panel are similarly formed. These ends of the transverse flanges F are disposed sub-

stantially in the plane of the inner face of the flange H, while the ends of the flange H are spaced inwardly relative to the bend line of the transverse flanges by substantially the height of the flanges. This relationship of the flanges and ends at the corners of the panel between which the flange H extends is effected by cutting from these corners of the sheet S rectangular corner portions each having an extent longitudinally of the sheet or panel substantially twice the flange height, and a transverse extent substantially equal to the height of the flanges. At their other ends, the transverse flanges F are inclined or angled, at substantially 45°, to the intersection of the bend lines of the transverse flanges with the bend line of the flange F formed on the other longitudinal edge of the panel, the ends of the longitudinal flange F similarly being angled from the edge thereof to the junctions of the bend lines of the adjacent flanges F. The angled ends of the flanges F are obtained by cutting off triangular corner portions of the sheet at the two corners between which the longitudinal flange F extends.

The inner panel I is formed with an upstanding flange H substantially identical to the flange H of the outer panel O as already described, rectangular corner portions as described in connection with the outer panel being cut from the corners between which the flange H extends. On the other three edges of the panel, rebent flanges are formed, each including an upstanding portion U of substantially the same height as the flange H, and an outwardly bent portion B extending at substantially right angles to the portion U and having a width substantially equal to the height of the portion U. The upstanding portions of the transverse rebent flanges have the inner faces thereof substantially in the common transverse planes of the corresponding ends of the flange H and the rebent flange on the other longitudinal edge of the panel. The upstanding portion of the longitudinal rebent flange is disposed substantially in the plane of the adjacent ends of the transverse rebent flanges. The adjacent ends of the upstanding portions of the rebent flanges and of the upstanding flange H thus substantially meet along lines substantially perpendicular to the plane of the panel, while the outwardly bent portions B of the rebent flanges lie in the same plane parallel to the panel. To provide for this relationship of the rebent flanges, square corner portions are cut from the corners between which the longitudinal rebent flange extends, each side of the square corner portions having a length or width substantially twice the height of the flange H or the upstanding portion U of the rebent flanges, or in other words an extent equal to the combined width of the portion B and height of the portion U.

Each of the door panels I and O is provided with a window aperture W and a lock aperture L, the corresponding apertures of the two panels being disposed in substantial registry in the completed door to accommodate a window, screen, or like insert in the opening provided by the apertures W, and a suitable door lock in the opening afforded by the apertures L. An opening for a lock or latch bolt may be punched in any suitable manner in the upstanding portion U of the longitudinal rebent flange of the inner panel.

In forming the door, suitable material such as wood may be disposed in the interior of panel I about the apertures W and L, and the remainder of the panel substantially filled with heat and sound insulating material, suitable adhesive being employed to secure these core or filler materials to the panel. The panel O is disposed over the open side of panel I with the two flanges H overlapping, adhesive being applied to effect securement of panel O to the filler materials, and the assembly held under pressure until the adhesive has set. The three upstanding flanges of the outer panel are then bent over the outwardly extending portions B of the rebent flanges of the inner panel so as to overlap and envelop the same, and thus interlock the two panels. Any suitable means,

such as spot welding, may be employed to further secure the panels together. It will be evident that the out-turned portions B of the inner panel, with the enveloping edge portions of the panel O, provide a flange about three edges of the door, on which suitable weather stripping or other gasket means may be mounted to assure weather-tightness. The overlapping flanges H in each of the panels, which may be backed by a wooden or like securing strip, provide for the hinged mounting of the door and may also carry gasket or weather strip means.

Referring now to FIG. 1, there is shown a press according to the invention, generally rectangular in plan and comprising a supporting framework formed in any suitable manner. The framework is shown as having a lower supporting portion including corner uprights 20 and horizontal, diagonal, and vertical brace elements 21, and an upper rigidifying portion spaced above the lower frame portion and defined by lower horizontal members 22 and suitably formed and disposed bracing members 23. The upper frame portion is spaced and supported above the lower frame portion by four vertical columns or rods 24 at the corners thereof. A horizontal fixed bed 25 in the form of a rectangular plate or the like facing downwardly and backed by the members 22, is secured at the upper ends of the columns or rods 24. The rods 24 are secured at their lower ends to a horizontal table 26 fixed on the lower frame portion. Mounted on the table 26 are means for applying the forming pressure in operation of the press, shown as a number of hydraulic cylinders 27, in this case six, each of which has telescoped therein an upwardly projectable piston 28. The pistons carry a movable bed or platen 29 of the press for movement thereof toward and from the fixed bed 25 by operation of the cylinders. The platen has apertures in its corner portions in which are mounted guide bushings or sleeves 30 slidable on the frame rods 24, which thus serve also to guide the vertical movements of the platen. At each end of the press, two transversely spaced pairs of toggle links 31 connected by a common horizontal pivot rod 32 are provided, one link of each pair being pivoted to the table 26 and the other to the underside of the platen. Only one pair of links 31 is shown at each end of the press. A longitudinally extending horizontal tie member connects the rods 32 to provide a toggle linkage for steadyng the movements of the platen. In the present case, the tie member is shown as comprising a tubular element 33 having extending longitudinally thereof a pair of rigidifying plate elements 34 welded thereto in diametrically opposed relation and disposed in a vertical plane. The cylinders 27 are supplied with fluid under pressure from a suitable source, not shown, through a control valve 35 having an operating lever 36 by which it may be moved to connect said source to branched conduit means 37 leading to the several cylinders to cause projection of the pistons, or to connect the conduit means to exhaust so as to effect collapse or retraction of the cylinders and pistons. An actuating cylinder 38 is mounted on the supporting framework adjacent the control valve 35, adapted to be operated by any suitable pressure fluid which may be that employed for cylinders 27, and having a piston rod 39 pivotally connected to the operating lever 36 of the valve, so that movement of piston 39 in one direction or the other may effect connection of the cylinders 27 to pressure or exhaust. Suitable electrical means, not shown, may be employed to effect operation of the cylinder 38 in response to actuation of a manual pushbutton or like switch to move the valve to a position connecting the pressure source to cylinders 27, and to cause reverse operation of the cylinder by automatic means to move the valve 35 to a position exhausting the cylinders 27. In this manner, a cycle of the press may be set in motion by manually controlled means to effect the desired forming movement of the platen 29 toward the bed 25 and the reverse movement to the open, idle, or loading position.

On the movable platen 29 is secured a forming die structure generally indicated at 40, suitably arranged for cooperation with a complementary die structure suitably secured on the fixed bed 25. As best shown generally in FIG. 3, and in detail in FIGS. 5 to 8, the die structure 40 comprises a number of die parts including a break or die member 42 extending adjacent one longitudinal edge of the platen 29, another bending die member 43 parallel to member 42 disposed adjacent the opposite platen edge, and a pair of die members 44 similar to the member 43 extending at right angles to the members 42 and 43 adjacent the ends thereof, transversely of the platen. The members 42 and 43 terminate short of the transverse planes of the members 44, and the members 44 similarly do not extend to the planes of the inner faces of the members 42 and 43, as will be clear from FIG. 3. The die member 42 is employed in forming the flanges H of the panels I and O, and the die members 43 and 44 in bending the other three flanges of each panel. Die blocks 45 secured on the platen 29 abutting the ends of the members 44 adjacent the die member 42 in effect extend those members to the plane of the inner face of member 42. Similar die blocks 46 are secured at the ends of the member 42, but do not extend to the planes of the inner faces of the die members 44, the spacing being substantially equal to the height of the upstanding flange F or flange portion U. The blocks in each case have plane bending faces flush with the inner faces of the die members which they abut, and shearing faces directed toward the planes of the adjacent die members. A shearing strip 47 is secured extending between the lower portions of each pair of blocks 45 and 46, with an outer face in the common plane of the bending face of block 46 and the shearing face of the block 45, as will be clear from FIGS. 3 and 8. Two shearing blocks 48 are secured on the fixed bed 25, each having a pair of rectangularly related shearing faces and being located to have these faces cooperate with the shearing faces of one of the pairs of blocks 45 and 46 and the associated strip 47. One of the blocks 48 is shown in FIG. 8. The die block construction at each end of member 42, with the cooperating block 48, cuts off the rectangular corner portion hereinabove described from a rectangular sheet S from which the panel is formed. The sheet S is of metal or other suitable self-sustaining material, such as aluminum, stainless steel, ordinary steel sheet, or the like, and is shown in FIG. 3 in phantom by broken line, in position supported on the die members 42, 43, and 44, ready for the forming operation. Depending upon the particular form and arrangement of the die means employed on the platen and bed, the sheet S is formed either into the inner door panel I or the outer door panel O, both substantially as shown in FIG. 4. Stops 49 are provided on the die member 43 and one of the members 44 to assure proper positioning of the sheet.

Die blocks are also secured at the adjacent ends of die members 43 and 44, the particular form depending upon which of the panels I and O is to be formed. In FIG. 3, block constructions for cutting both square and triangular corner portions are shown. At the corner defined at the left end of member 43 as viewed in the figure and the adjacent end of the adjacent member 44, and as shown more clearly in FIG. 7, there is provided a pair of substantially rectangular die blocks 50, one at each of the adjacent ends of members 43 and 44. The outer end face of each block 50 serves as a shearing or cutting face and is spaced from the plane of the inner or bending face of the die member toward which it is directed, the inner face of each block 50 being substantially flush with the die member which it abuts. A pair of shearing strips 51 similar to strip 47 are employed in a similar manner, each strip abutting the inner face of one of the blocks 50 and extending with an outer face in the plane of the cutting face of the block. The length of each strip

corresponds to the space between the inner face of the block it abuts and the plane of the cutting face of the other block, which space is equal to the height of the flange F or flange portion U. On the bed 25 are secured two shearing die blocks, not shown, but similar to the blocks 48 in form, location relative to the pairs of blocks 50, and operation. The die block structure just described operates to cut the square corner portions from the sheet in forming of a panel I.

At the right end of die member 43 as viewed in FIG. 3, a die block structure for cutting a triangular corner portion from sheet S in forming an outer panel O is shown. FIGS. 5 and 6 illustrate this structure in greater detail, and show the loading and the shearing positions of the parts. In respectively abutting relation to the adjacent ends of the die members 43 and 44, die blocks 52 are secured. The blocks 52 are generally similar to the rectangular or cubical blocks 45, 46 and 50 previously shown and described, but each has a triangular projecting portion 53 defined by the inner face thereof and a diagonally extending surface. The blocks 52 are arranged with their inner faces flush with the inner faces of the die members they abut, and with the apices of the triangular portions substantially in contact, so that the diagonal surfaces extend in a common plane diagonally of the corner defined by the inner block faces. A shear die block 54 of rectangular form is mounted on the press bed 25 in a position such that one of its cutting faces extends substantially in the same plane as the diagonal surfaces of the triangular portions 53 of blocks 52, as best shown in FIG. 5, so that it may cooperate therewith to shear off a triangular corner portion of the sheet S as the die parts move relative to each other from the position of FIG. 5 to that of FIG. 6. The die block 54 may, if desired, be the same block employed for cooperation with the die blocks 50, being removably mounted on the bed 25 to allow of its positioning either in the diagonal position of FIGS. 5 and 6 or a position substantially like that of the block 48 in FIG. 8, with faces parallel to the planes of the shearing faces of the cooperating die blocks 50.

It will be appreciated that both the die block structures incorporating the blocks 50 and the blocks 52 are not actually used at the same time, two similar structures 45 with the blocks 50 being employed when an inner panel is to be formed, and two structures with the blocks 52 being used when an outer panel is to be formed. By the use of bolts or like means to secure the various parts, as well known in the art, the several blocks and associated parts may easily be mounted and removed.

Within the rectangular space defined by the die members 42, 43, and 44 there is disposed an ejector plate 55 having one longitudinal edge in the plane of the inner face of the die member 42, the other three edges thereof being equally spaced from the inner faces of the members 43 and 44. The ejector plate 55 is of less thickness or height than the members 42, 43, and 44, and has a number of ejector rods 56 depending therefrom. The rods 56 are secured to the plate 55 by the screwing of reduced threaded upper ends thereof in threaded apertures 57 extending through the plate, as clearly shown in FIGS. 9 and 10. The rods extend through suitable apertures in the platen 29 and through guide tubes 58 secured as by welding to the lower face of the platen in registry with the apertures. An enlargement or collar 59 is provided on each rod below the associated tube 58 to limit upward movement of the rod relative to the platen by engagement with the tube, the arrangement being such that the highest relative level of the ejector plate is the plane of the upper surfaces of the die members 42, 43, and 44. When the press is in open or loading position, the rods 56, of which four are employed in the present instance, engage on the table 26 and hold the ejector plate 55 elevated to the level of the upper faces of the die members, while when the platen 29 is raised in a forming operation, the

rods 56 are lifted off the table 26 and the ejector plate thus brought to a position resting on the platen. This will be clear from FIGS. 9 and 10, in which the lowered and raised positions of the platen, and the corresponding positions of ejector plate 55, are illustrated. In its elevated position level with the top surfaces of the members 42, 43, and 44, the ejector plate aids in supporting the metal sheet S. The sheet S is somewhat larger than the area defined by the members 42, 43, and 44, projecting outwardly of the inner faces of these die members by a distance substantially equal to the height of the flanges F and H or upstanding flange portion U to be formed on the edges. The ejector plate member has a rectangular aperture 60 formed therein corresponding to aperture W to be cut in the sheet S. A smaller rectangular aperture 61 is also provided in the plate 55, corresponding to the door lock aperture L of the panel. Another aperture 62 similar to apertures 60 may be provided, if desired. Within the outline of the aperture 60, and in slight clearance relation therewith, there is secured on the platen 29 a rectangular shearing die 63 provided by suitable plates or bars of somewhat greater thickness or height than the ejector member 55, as best shown in FIGS. 9 and 10. Within the outline of the aperture 61 is a shear block 64 of slightly smaller dimensions, secured on the platen, and like the die 63 having a somewhat greater height than the ejector plate. The aperture 61, as evident from FIG. 3, is located midway of the end die members 44, or midway of the length of the sheet S when disposed in forming position as indicated by the broken lines in the figure, and is spaced slightly from the die member 43.

The die parts structure, generally designated 65, secured on the bed 25 of the press, as already indicated, complements the die structure 40 on the platen 29 just described, and engages therewith upon upward movement of the platen to engage the parts for forming the sheet S disposed therebetween into an inner panel I or outer panel O, as the case may be. The structure 65 includes die means cooperating with each of the several die members and elements mounted on the platen 29. Specifically, in addition to the shearing or cutting blocks already mentioned, there is secured on the lower face of the bed 25 an elongated bending die member 66 extending parallel to and spaced inwardly relative to the bending die member 43, the spacing being substantially equal to the thickness of the sheet S, as will appear from FIGS. 9 to 11 inclusive. A pair of similar die members 67 are secured on the bed in substantially the same relationship to the end die members 44, as shown in FIGS. 5 and 8. Another generally similar member 68 is provided on the bed parallel to the die member 42, the outer face of member 68 being spaced inwardly of the plane of the inner face of member 42 by the thickness of sheet S. Each of the die members 66 and 67 has a rabbet 68 formed in the lower outer corner edge thereof, the rabbet being defined by a pair of rectangularly related surfaces each of a width substantially equal to the flange height. A die bar 70 of substantially square cross section is removably secured in the rabbet of each member 66 and 67, the die bar 70 having each of its sides of such width that it fits in the rabbet with two adjacent faces engaging against the rabbet surfaces and its other two faces flush with the outer and lower surfaces of the die member 66 or 67 to which it is secured. The rabbets 69 and die bars 70 extend for the full length of the respective die members 66 and 67, which are of lengths equal to the full distance between the die members between which the members 66 and 67 extend. That is, the die members 66, 67 and 68 engage each other at their respectively adjacent ends to define closed corners, as best shown in FIG. 8.

Also secured on the press bed 25 are four shear die members 71 rectangularly arranged for cutting cooperation with the shearing die 63, each of the die members 71 being mounted with the inner face substantially in the

plane of the outer face of the corresponding side of die 63, as clearly shown in FIGS. 9, 10, and 12. The die members 71 cooperate with the shearing die 63 to cut a portion S' (FIG. 10) from the sheet to form the opening W. It will be noted that as exaggeratedly shown in FIG. 12, each of the members 71, only one of which is fully shown, has a lower cutting edge 72 which at its central portion is slightly curved, the curved portion merging with straight portions of the edge which extend outwardly and upwardly at a slight angle. By this construction, each of the members in the forming movement of the press first engages the sheet S at substantially a point for holding contact therewith, then cuts the sheet at this point of contact, continuing the cutting in a progressive shearing action as the remainder of the edge engages the sheet. Drawing of the sheet material during the cutting operation is avoided, and easier and smoother cutting of the sheet, and a cleaner cut, are provided by this construction and action. The shearing die 63 may have its shearing edges similarly formed. The shear die members 71 are shown in the present instance as secured to the bed 25 by means of a suitable mounting plate 73 so that they may quickly and easily be attached and removed as a unit, although of course any appropriate means may be employed for this purpose. Similar shear die members, not shown, are provided for cooperation with the shear block 64 to cut the aperture L in the sheet, although the same edge formation is not necessarily employed in view of the relatively small size of the sheet portion cut from the sheet thereby. A rectangular stripper 74 (FIGS. 9 and 10) is provided disposed within the area defined by the die members 71 and presenting four edges each substantially engaging against the inner face of one of the shear die members 71 to prevent the portion S' from remaining frictionally engaged with the members 71. The stripper 74 is arranged for vertical movement relative to the bed 25, having a suitable number of guide rods 75, only one of which is shown, extending upwardly therefrom through suitable registering apertures in the mounting plate 73 and bed 25, the rods sliding in the apertures to allow corresponding movement of the stripper and having enlarged heads 76 or the like on their upper ends to limit the downward movement of the stripper. Suitable means such as a plurality of coil springs 77, only one of which is shown, are engaged between the mounting plate 73 and the stripper 74 to urge the stripper positively away from the mounting plate so as to overcome any friction tending to hold the sheet portion S' within the shear die members 71. The stripper 74, as will be clear from FIG. 10, moves relatively upward in the cutting action, by reason of the shearing die 63 forcing the sheet portion S' and the stripper upwardly above the level of the die members 71.

In operation of the press, the rectangular sheet S is disposed as shown in FIG. 3 on the die parts or members mounted on the platen, in the lowered position thereof corresponding to the open or loading condition of the press, and the control valve 35 is operated by means of the actuating cylinder 38 and its electrical control circuit to effect flow of fluid under pressure to the cylinders 27 so as to cause projection of the pistons 28, lifting the platen with the die means thereon and the sheet S overlying the same upwardly into pressing engagement with the die means on the bed 25. As will be readily evident from FIGS. 5 to 8 inclusive, the corner portions 65 of the sheet will be sheared away by the cooperating die blocks on the platen and bed, as previously described. In the case of the square and rectangular corner portions, the shearing is not completed until the upper edges of the strips 47 or 51 have moved upwardly past the lower edges of the die blocks on the bed. The die blocks 45 and 46 and the shear strip 47, with the cooperating die block 48, by which rectangular corner portions of the sheet are cut away at the ends of the hinge-edge forming die portions are the same for either the inner panel I or the outer panel O, and need not be changed when one or

the other panel is to be formed. The pairs of die blocks 52 and the cooperating block 54 on the bed for shearing off the triangular corner portions of the sheet when an outer panel is to be formed therefrom, however, must be replaced by the pairs of die blocks 50 on the platen and the cooperating die blocks on the bed which serve to sever the square corner portions from the sheet when the inner panel I is to be formed therefrom. Of course, the reverse is true when an outer panel O is to be formed after the press has been employed to form an inner door panel I. Similarly, the die bars 70 must be secured in the rabbets 69 of the bending die members 66 and 67 on the bed when an outer door panel is to be formed, and mounted on the inner faces of the die members 43 and 44 on the platen, as shown in FIG. 11, when an inner panel I is to be formed. It will be evident, that each of the strips 47 and 51 might be formed integral with the associated block 45 or 50, and in any case may be considered as in effect forming a cutting portion thereof.

Assuming that an outer panel O is to be formed and that the die means have been employed as described, the sheet S on the platen is raised by upward movement of the platen from the full-line position of FIGURE 9 to the dotted-line position, in the course of which the ejector member is engaged by the platen and raised thereby. In this raised position, the sheet S supported on the die means on the platen has just come into contact with the bending die members 66, 67, and 68 of the bed, including the die bars 70, and also with the shearing die members 71 and the stripper 74, as well as with the shear die members which cooperate with the shear block 64 to form the door lock aperture L. At this same point in the upward movement of the sheet on the platen, the corner die blocks 48 and 54 on the press bed are also in contact with the upper surface of the sheet, ready to begin the shearing of the rectangular and triangular portions. As the upward movement of the sheet continues from the momentary contacting position just described, the two pairs or sets of corner die blocks 45 and 46 and the strips 47 cooperate with the die blocks 48 to effect shearing of the rectangular corner portions from the sheet, the shearing however not being complete until each block 48 comes into shearing relation with the shear strip 47 which spans the gap between the associated blocks 45 and 46. At the same time, each die block 54 with its diagonally arranged shearing edge cooperates with the diagonal shearing face or edge provided by the triangular portions 53 of the die blocks 52, at each of the other corners of the sheet, to sever the triangular corner portions therefrom which provide the angled ends of the longitudinal upstanding flanges F of the outer panel. While the several corner portions are being severed, the flanges F and H of the outer panel O are being formed by cooperation of the bending die members 42, 43, and 44 on the platen and the corresponding die members 68, 66, and 67 on the bed. By reason of the slight spacing between the planes of the outer faces of the die members on the bed and the inner faces of the corresponding die members on the platen, as shown in FIGS. 9 and 10, the edge portions of the sheet extending outwardly beyond the inner faces of the bending die members on the platen are not sheared, but are bent upwardly, as shown in FIGS. 9 and 10, in which the longitudinal flange F is shown as being formed by bending of this marginal portion of the sheet as the longitudinal die member 43 moves upwardly beyond the lower face of the die member 66. It will be understood that the folding of the other flange F and of the flange H is effected in the same manner as shown and described in connection with the longitudinal flange F. The cutting of the window and lock apertures in the sheet does not begin until the platen has moved to the point at which the shearing die 63 engages the lower surface of the sheet and continues upwardly to force the sheet against the curved cutting edges 72 of the shearing die members 71, against the force of

the springs 77, to effect the progressive shearing or cutting of the several sides of the opening. The door lock opening is similarly cut at this time, and in substantially the same manner.

- 5 This completes the forming of the panel prior to the employment thereof in the final door assembly, and the platen 29 now is caused to descend, preferably by automatic means which actuate the cylinder 38 to cause movement of the control valve 35 to a position effecting
- 10 exhaust of the pressure fluid from the cylinders 27, so that the pistons 28 are retracted. If desired, of course, manually controlled means may be employed to actuate the cylinder 38, or the cylinder and its connection to the valve operating lever 36 may be eliminated altogether, and the valve manually operated as and when desired. As the platen descends, the springs 77 urge the stripper 74 downwardly to force the portion S' of the sheet which has been severed therefrom in the formation of the window opening W downwardly out of engagement with the
- 15 shearing die members 71, so that this portion of the sheet will descend with the remainder of the sheet. As has already been indicated, the portion of the sheet severed in the formation of the door lock opening, due to its relatively small size, does not necessarily require a stripper
- 20 construction because it may readily be withdrawn from the shearing structure by hand if it becomes lodged therein, but a stripping arrangement generally similar to that of the stripper 74 may be provided if desired. When the platen reaches its lowermost position, it is halted by the
- 25 full retraction of the pistons 28 within the cylinders 27, and also by engagement of the lower ends of the tubular guides 58 on the collars 59 of the ejector rods 56 depending from the ejector plate or member 55, the lower ends of the rods engaging on the table 26, so that a positive
- 30 and steady positioning of the platen in its lowermost position is obtained. During the descent of the platen, as the rods 56 come into engagement with the table 26, the ejector plate 55 is held against further downward movement, while the platen and the die means thereon
- 35 are free to continue their movement until the ejector guide tubes 58 engage the rod collars 54, with the result that the ejector plate and the sheet S, now in the form of the panel O, is brought to the level of the upper surfaces of
- 40 the die members 42, 43, and 44, so that it may readily be removed from the press. After removal of the portions cut from the sheet in the formation of the window and lock openings, another sheet S may be disposed on the platen-carried die means and the cycle repeated to form another outer door panel O, in the manner just
- 45 described.
- 50

- 55 If an inner panel I is to be formed from the sheet S, the die bars 70 are secured on the inner faces of the respective bending die members 43 and 44, as shown in FIG. 11, and the pairs or sets of corner die blocks 50 and shear strips 51, with the cooperating blocks of the die means 65, are secured on the platen and bed. When the control valve is operated to effect projection of the pistons 28 from the cylinders 27 to raise the platen, the ejector member or plate 55 is engaged from beneath and
- 60 raised by the platen, the sheet as it is raised by the die means on the platen having the rectangular and square corner portions cut therefrom by the several die block structures already described, substantially in the manner described in connection with the forming of the outer panel O. Substantially simultaneously or contemporaneously with the severing of the corner portions, the rebent flanges are formed of the marginal portions of the sheet by the cooperation of the rectangularly related surfaces of the rabbets 69 of the die members 66 and 67 on the
- 65 bed and the inner and upper faces of the die bars 70 mounted on the die members 43 and 44, substantially as shown in FIG. 11. It will be apparent that by reason of the slight spacing between the planes of the outer faces of the members 66 and 67 and the inner faces of the die members 43 and 44, the die bars when secured on
- 70
- 75

the die members 43 and 44 will similarly have a space substantially equal to the thickness of the sheet between the planes of their inner faces and the planes of the vertical rabbet-defining surfaces, and the bars 70 are secured at such a level that their upper faces are similarly spaced from the horizontal rabbet-defining surfaces of the members 66 and 67 when the lower faces of those members have come into engagement with the upper surface of the sheet in opposition to the upper surface of the ejector plate 55 which underlies the sheet. The cutting of the window and lock openings in the sheet is effected in the manner already described in connection with the formation of the outer door panel O. The lowering of the platen and the positioning of the sheet by the ejector plate a convenient level for removal follows as in the case of the outer panel.

It is pointed out that it is necessary to reverse the sheet from which an inner panel is to be formed relative to the sheet from which an outer panel is formed. The panels must be so formed that when they are in the assembling relation generally indicated in FIG. 4, the flanges F and H of panel O extend toward the upstanding flange portions U and flange H of panel I, and in planes parallel thereto, with the flanges H at corresponding edges of the panels and the apertures W and L of the two panels in respectively registering relation. Since as explained hereinabove both panels are formed with the flanges H at the same side or edge of the die means and the upstanding flange portions and flanges of both are formed by folding of the sheet edges upwardly, it will be apparent that if each panel were also formed with the aperture W at the left-hand portion thereof as viewed in FIG. 3, the panels could not be assembled as explained hereinabove. To provide for the necessary relative reversal of one panel relative to the other without requiring a time-consuming and tedious rearrangement of the die means on the platen and on the bed, the ejector member or plate 55 and the shearing die 63 associated with the opening 60 thereof are arranged for ready repositioning on the platen. In order properly to form either an inner or outer panel after the press has been used to form the other type of panel, with the ejector plate 55 in the position shown in FIG. 3, having the opening 60 at the left end portion thereof, the member 55 is reversed in position so that the opening 60 is at the right hand portion thereof, or in other words at the right hand portion of the platen. This is accomplished by unscrewing the ejector rods 56 from the threaded openings 57 in the ejector plate, so that the ejector member may be removed from the platen, turned about its transverse axis to position the previously upper face thereof as the lower face, then replacing the ejector plate on the platen, and again screwing the upper ends of the ejector rods 56 into the threaded openings 57 of the ejector, this time from the opposite face of the plate 55. The opening 60 now of course is located at the right-hand portion of the forming structure. The die 63, being bolted or otherwise removably secured on the platen, may readily be detached and secured in its new position within the outline of aperture 60 either before or after the reversed ejector 55 is disposed in its new position. It will be noted that the threaded apertures through the ejector member are spaced the same distance from the adjacent ends of the member, and from the transverse bending die members 44, so that there is no difficulty in the repositioning of the ejector plate, and the plate is located in exactly the same relation to the die members 42, 43, and 44 regardless of the position of the opening 69.

In the present instance, the lock opening 61 is shown as located exactly half-way between the ends of the ejector plate 55, so that it is not necessary to make any provision with regard to it because of the reversal of the ejector plate. If the opening 61 were not midway of the length of the ejector member, however, it would be necessary only to remove the shear block 64 and relocate

it on the platen at a position such as to come within the outline of the opening 61, substantially in the manner of the shear die 63 in connection with the window opening 60.

Where herein the various parts of the inventive structure have been referred to as located in a right or left, or an upper or lower position, it will be understood that this is done solely for the purpose of facilitating the description, and that such references relate only to the relative positions of the parts as shown in the drawings.

Also, it is to be understood that the illustrated embodiment of the invention is exemplary, and that many changes and modifications may be made therein without departing from the invention, and that the invention is not to be limited except as required by the scope and spirit of the appended claims.

I claim:

1. In a press having complementary die members relatively movable opposingly into engaged relation for bending marginal portions of adjacent edges of a metal sheet to provide thereon either upstanding flanges of predetermined height having at least one end inclined or rebent flanges each having an upstanding portion of substantially said height and an outturned portion extending from said upstanding portion a distance substantially equal to said height, for cutting off a corner portion of the sheet between said adjacent edges prior to the forming of said flanges, and for contemporaneously cutting a substantially rectangular opening in the sheet, first bending die means on a first of said die members having substantially parallel to the direction of said relative movement a plane surface of an extent in said direction at least equal to said height, second bending die means on the second die member having a first plane face parallel to the plane of said plane surface and spaced therefrom by substantially the thickness of said sheet and also having a second plane face normal to said first face, said second bending die means having therein a dihedral rabbet defined by a pair of rectangularly related surfaces each having a width substantially equal to said height with one extending substantially parallel to said first face and the other substantially parallel to said second face, a die bar of substantially square cross section each side of which has a width substantially equal to said height, said die bar being selectively mountable either on said second die means in said rabbet with two adjacent sides thereof substantially flush with the corresponding faces of said second die means or on said first die means projecting from the plane surface with one side substantially normal thereto and a side adjacent said one side parallel to the plane surface and spaced by substantially the thickness of said sheet from the plane of said first rabbet surface, means for detachably mounting said bar selectively on one of said bending die means, means on at least one of said first and second die means for supporting therebetween in a plane substantially normal to the planes of said plane surface and said first face a metal sheet edge portion which measured from said plane surface to the adjacent sheet edge has a width substantially equal to said height, said bar when mounted in said rabbet cooperating with said plane surface upon said die member movement to bend said edge portion into an upstanding flange of said predetermined height and when mounted on said plane surface cooperating with said rabbet-defining surfaces upon said die member movement to bend the portion of the sheet adjacent said edge portion to a position substantially normal to the edge portion and to the body of the sheet to provide the upstanding portion of a rebent flange having said edge portion as the outturned portion, rectangularly arranged first cutting die means on one of said die members defining an outline corresponding to an opening to be cut in the sheet and affording support for the sheet inwardly from said outline, second cutting die means on the other of the die members rectangularly arranged to telescope in close-fit-

ting relation with said first cutting die means upon said die member movement to cut the sheet along said outline for severing therefrom a portion of the sheet to provide said opening therein, at least one of said first and second cutting die means comprising shear elements each having a curved cutting edge affording a progressive shearing of the sheet, two pairs of cutting elements selectively disposable on one of said die members positioned to have said sheet corner portion disposed adjacent thereto upon insertion of said sheet in the press, one of said pairs when disposed on said die member having the cutting elements thereof presenting a pair of rectangularly related plane surfaces each parallel to the direction of movement of the die members and extending in a plane parallel to the line of one of said adjacent edges and intersecting the line of the other edge, the projected planes of said plane surfaces defining on the sheet a square corner portion of an extent inward from each of said edges substantially equal to the combined height and width of said upstanding and outturned portions respectively of said rebent flange, the other of said pairs of cutting elements when disposed on said one die member having the cutting elements thereof presenting a pair of aligned plane surfaces extending diagonally relative to said adjacent sheet edges, the projected planes of said diagonal plane surfaces defining on the sheet a triangular corner portion of an extent along each of said edges substantially equal to said height, a cutting die block on the other of said die members having a pair of rectangularly related plane surfaces each parallel to said direction of die member movement and of at least said corner portion extent, said die block being detachably securable on said other die member selectively in one position with said plane surfaces thereof respectively in shearing relation with the plane surfaces of said one pair of cutting elements or in a second position with one of said plane surfaces thereof extending diagonally relative to said adjacent edges in shearing relation with said diagonal plane surfaces of the other pair of cutting elements, means for selectively securing said pair of cutting elements detachably on said one die member, and means for detachably securing the cutting die block on said other die member selectively in one of said positions, whereby preliminary to formation of rebent flanges on adjacent edges of the sheet the first cutting element pair may cooperate with said die block in said first position thereof to shear said rectangular corner portion from the sheet, and prior to formation of upstanding flanges on said edges said other cutting element pair may cooperate with the die block in said second position thereof to shear said triangular corner portion from the sheet.

2. In a press having complementary die members relatively movable opposingly into engaged relation for bending marginal portions of adjacent edges of a metal sheet to provide thereon either upstanding flanges of predetermined height having at least one end inclined or rebent flanges each having an upstanding portion of substantially said height and an outturned portion extending from said upstanding portion a distance substantially equal to said height, for cutting off a corner portion of the sheet between said adjacent edges prior to the forming of said flanges, and for contemporaneously cutting a substantially rectangular opening in the sheet, first bending die means on a first of said die members having substantially parallel to the direction of said relative movement a plane surface of an extent in said direction at least equal to said height, second bending die means on the second die member having a first plane face parallel to the plane of said plane surface and spaced therefrom by substantially the thickness of said sheet and also having a second plane face normal to said first face, said second bending die means having therein a dihedral rabbet defined by a pair of rectangularly related surfaces each extending substantially parallel to one of said faces and having a width substantially equal to said height, a

die bar of substantially square cross section each side of which has a width substantially equal to said height, said bar being selectively mounted either on said second die means in said rabbet with two adjacent sides thereof substantially flush with the corresponding faces of said second means or on said first die means projecting from the plane surface with one side substantially normal thereto and a side adjacent said one side parallel to the plane surface and spaced by substantially the thickness of said sheet from the plane of the rabbet surface parallel to said first face of the second die means, means for detachably mounting said bar selectively on one of said bending die means, means on at least one of said first and second bending die means for supporting therebetween in a plane substantially normal to the planes of said plane surface and said first face a metal sheet edge portion which measured from said plane surface to the adjacent sheet edge has a width substantially equal to said height, said bar when mounted in said rabbet cooperating with said plane surface upon said die member movement to bend said edge portion into an upstanding flange of said predetermined height and when mounted on said plane surface cooperating with said rabbet-defining surfaces upon said die member movement to bend the portion of the sheet adjacent said edge portion to a position substantially normal to the edge portion and to the body of the sheet to provide the upstanding portion of a rebent flange having said edge portion as the outturned portion, rectangularly arranged first shearing die means on one of said die members defining an outline corresponding to an opening to be cut in the sheet, second shearing die means on the other of the die members rectangularly arranged to telescope in close-fitting relation with said first shearing die means upon said die member movement to cut the sheet along said outline for severing therefrom a portion of the sheet to provide said opening therein, at least one of said first and second shearing die means comprising shear elements each having a curved cutting edge affording a progressive shearing of the sheet, two pairs of cutting elements selectively disposable on one of said die members positioned to have said sheet corner portion disposed adjacent thereto upon insertion of said sheet in the press, one of said pairs when disposed on said die member presenting a pair of aligned plane surfaces extending diagonally relative to said adjacent sheet edges, the projected planes of said diagonal plane surfaces defining on the sheet a triangular corner portion of an extent along each of said edges substantially equal to said height, a pair of cutting die blocks selectively securable on the other of said die members, one of said die blocks having a pair of rectangularly related plane surfaces each parallel to said direction of die member movement and of at least said rectangular corner portion extent along said edges, the other of said die blocks having a plane surface parallel to said direction of movement and extending diagonally relative to said adjacent sheet edges with the plane thereof defining with said edges a triangle corresponding to said triangular corner portion, said one die block being detachably securable on said other die member in position with said plane surfaces thereof respectively in shearing relation with the plane surfaces of said one pair of cutting elements, said other die block being detachably securable on the other die member with said plane surface thereof in shearing relation with said

diagonal plane surfaces of the other pair of cutting elements, means for detachably securing said cutting elements selectively on said one die member, and means for detachably securing the die blocks selectively on said other die member whereby the first cutting element pair may cooperate with said one die block to shear said square corner portion from the sheet and said other cutting element pair may cooperate with the other die block to shear said triangular corner portion from the sheet.

3. Structure substantially as defined in claim 2, in which each of the cutting elements of said one pair is spaced from said plane surface of the other cutting element thereof, and including a shear strip having a plane face flush with the plane surface of one of the cutting elements of said one pair and of appreciably less extent than such plane surface in said direction of movement and extending from said one element at least to the plane of the plane surface of said other cutting element.

4. In a press having complemental die members relatively movable opposedly into engaged relation for bending a marginal portion of a metal sheet to provide thereon either an upstanding flange of predetermined height or a rebent flange having an upstanding portion of substantially said height and an outturned portion extending from said upstanding portion a distance substantially equal to said height and contemporaneously cutting a substantially rectangular opening in the sheet, first die means on a first of said die members having substantially parallel to the direction of said relative movement a plane surface of an extent in said direction at least equal to said height, second die means on the second of said die members having a first plane face parallel to the plane of said plane surface and spaced therefrom by substantially the thickness of said sheet and also having a second plane face normal to said first face, said second die means having therein a dihedral rabbet defined by a pair of rectangularly related surfaces each extending substantially parallel to one of said faces and having a width substantially equal to said height, a die bar of substantially square cross section each side of which has a width substantially equal to said height, said bar being selectively mounted either on said second die means in said rabbet with two adjacent sides thereof substantially flush with the corresponding faces of said second means or on said first die means projecting from the plane surface with one side substantially normal thereto and a side adjacent said one side parallel to the plane surface and spaced by substantially the thickness of said sheet from the plane of the rabbet surface parallel to said first face of the second die means, means for detachably mounting said bar selectively on one of said die means, means on at least one of said first and second die means for supporting therebetween in a plane substantially normal to the planes of said plane surface and said first face a metal sheet edge portion which measured from said plane surface to the adjacent sheet edge has a width substantially equal to said height, said bar when mounted in said rabbet cooperating with said plane surface upon said die member movement to bend said edge portion into an upstanding flange of said predetermined height and when mounted on said plane surface cooperating with said rabbet-defining surfaces upon said die member movement to bend the portion of the sheet adjacent said edge portion to a position substantially normal to the edge portion and to the body of the sheet to provide the upstanding portion of a rebent flange having said edge portion as the outturned portion, rectangularly arranged first die elements defining an outline corresponding to an opening to be cut in the sheet and affording support for the sheet inwardly from said outline, second die elements on the other of the die members rectangularly arranged to telescope in close-fitting relation with said first die elements upon said die member movement to cut the sheet along said outline for severing therefrom a portion of the sheet to provide said opening therein, at least one of said first and

second die elements comprising shear elements each having a curved cutting edge affording a progressive shearing of the sheet.

5. In a press having complemental die members relatively movable opposedly into engaged relation for bending a marginal portion of a metal sheet to provide thereon either an upstanding flange of predetermined height or a rebent flange having an upstanding portion of substantially said height and an outturned portion extending from said upstanding portion a distance substantially equal to said height and contemporaneously cutting an opening in the sheet, first die means on a first of said die members having substantially parallel to the direction of said relative movement a plane surface of an extent in said direction at least equal to said height, second die means on the second of said die members having a plane face parallel to the plane of said plane surface and spaced therefrom by substantially the thickness of said sheet, a dihedral rabbet defined in said second die means having therein a pair of rectangularly related surfaces one of which extends substantially parallel to said face and has a width substantially equal to said height, a die bar of a cross section providing two adjacent sides corresponding to said rabbet surfaces and a third side parallel to one of said two sides, said bar being selectively mounted either in said rabbet with said two adjacent sides thereof engaging said rabbet surfaces and said third side substantially flush with said face of said second means or on said first die means projecting from the plane surface with one of said two sides substantially normal thereto and said third side parallel to the plane surface and spaced by substantially the thickness of said sheet from the plane of said one rabbet surface, means for detachably mounting said bar selectively on one of said die means, means on at least one of said first and second die means for supporting therebetween in a plane substantially normal to the planes of said plane surface and said plane face a metal sheet edge portion which measured from said plane surface to the adjacent sheet edge has a width substantially equal to said height, said bar when mounted in said rabbet cooperating upon said die member movement with said plane surface to bend said edge portion into an upstanding flange of said predetermined height and when mounted on said plane surface cooperating upon said die member movement with said rabbet surfaces to bend the portion of the sheet adjacent said edge portion to a position substantially normal to the edge portion and to the body of the sheet to provide the upstanding portion of a rebent flange having said edge portion as the outturned portion, first shear die means on one of the die members corresponding in outline to an opening to be cut in the sheet, and second shear die means on the second of the die members, said first and second shear die means being arranged to telescope in close-fitting relation upon relative movement of the die members toward each other to sever a portion from the sheet to provide said opening therein.

6. In a press having complemental die members relatively movable opposedly into engaged relation for bending marginal portions of adjacent edges of a metal sheet to provide thereon either upstanding flanges of predetermined height or rebent flanges each having an upstanding portion of substantially said height and an outturned portion extending from said upstanding portion a distance substantially equal to said height and for cutting off a corner portion of the sheet between said adjacent edges, first die means on a first of said die members having substantially parallel to the direction of said relative movement a plane surface of an extent in said direction at least equal to said height, second die means on the second of said die members having a first plane face parallel to the plane of said plane surface and spaced therefrom by substantially the thickness of said sheet and also having a second plane face normal to said first face, said second die means having therein a dihedral rabbet defined by a pair of rectangularly related surfaces having a width

substantially equal to said height with one extending substantially parallel to said first face and the other substantially parallel to said second face, a die bar of substantially square cross section each side of which has a width substantially equal to said height, said bar being selectively mounted either on said second die means in said rabbet with two adjacent sides thereof substantially flush with the corresponding faces of said second means or on said first die means projecting from the plane surface with one side substantially normal thereto and a side adjacent said one side parallel to the plane surface and spaced by substantially the thickness of said sheet from the plane of said one rabbet surface, means for detachably mounting said bar selectively on one of said die means, means on at least one of said first and second die means for supporting therebetween in a plane substantially normal to the planes of said plane surface and said first face a metal sheet edge portion which measured from said plane surface to the adjacent sheet edge has a width substantially equal to said height, said bar when mounted in said rabbet cooperating with said plane surface to bend said edge portion into an upstanding flange of said predetermined height upon said die member movement and when mounted on said plane surface cooperating upon said die member movement with said rabbet surfaces to bend the portion of the sheet adjacent said edge portion to a position substantially normal to the edge portion and to the body of the sheet to provide the upstanding portion of a rebent flange having said edge portion as the outturned portion, two pairs of cutting elements selectively disposable on one of said die members positioned to have said sheet corner portion disposed adjacent thereto upon insertion of said sheet in the press, one of said pairs when disposed on said die member presenting a pair of rectangularly related plane surfaces each parallel to said direction of movement and extending in a plane parallel to the line of one of said adjacent edges and intersecting the line of the other edge, the projected planes of said plane surfaces defining on the sheet a rectangular corner portion of an extent inward from each of said edges substantially equal to the combined height and width of said upstanding and outturned portions respectively of said rebent flanges, the other of said pairs of cutting elements when disposed on said one die member presenting a pair of aligned plane surfaces extending diagonally relative to said adjacent sheet edges, the projected planes of said diagonal plane surfaces defining on the sheet a triangular corner portion of an extent along each of said edges substantially equal to twice said height, a pair of die blocks selectively securable on the other of said die members, one of said die blocks having a pair of rectangularly related plane surfaces each parallel to said direction of die member movement, said one die block being detachably securable on said other die member in a position with said plane surfaces thereof respectively in shearing relation with the plane surfaces of said one pair of cutting elements, the other die block having a plane surface parallel to said direction of movement, said other die block being detachably securable on said other die member in a position with said plane surface thereof extending diagonally relative to said adjacent edges in shearing relation with said diagonal plane surfaces of the other pair of cutting elements, means for detachably securing said cutting elements selectively on said one die member, and means for detachably securing the die blocks on said other die member selectively in said respective positions thereof, whereby prior to formation of rebent flanges on adjacent edges of the sheet the first cutting element pair may cooperate with said one die block to shear said square corner portion from the sheet, and prior to formation of upstanding flanges on said edges said other cutting element pair may cooperate with the other die block to shear said triangular corner portion from the sheet.

7. In a press having complementary die members relatively movable opposedly into engaged relation for bend-

ing marginal portions of adjacent edges of a metal sheet to provide thereon either upstanding flanges of predetermined height having at least one end inclined or rebent flanges each having an upstanding portion of substantially said height and an outturned portion extending from said upstanding portion a distance substantially equal to said height, and for cutting off a corner portion of the sheet between said adjacent edges prior to the forming of said flanges, first die means on a first of said die members having substantially parallel to the direction of said relative movement a plane surface of an extent in said direction at least equal to said height, second die means on the second die member having a plane face parallel to the plane of said plane surface and spaced therefrom by substantially the thickness of said sheet, a dihedral rabbet defined in said second die means by a pair of rectangularly related surfaces one of which extends substantially parallel to said face and each having a width substantially equal to said height, a die bar of a cross section providing two adjacent sides corresponding to said rabbet surfaces and a third side parallel to one of said two sides, said bar being selectively mounted either in said rabbet with said two adjacent sides thereof engaging the rabbet surfaces and said third side substantially flush with said face of said second means or on said first die means projecting from the plane surface with one of said two sides substantially normal thereto and said third side parallel to the plane surface and spaced by substantially the thickness of said sheet from the plane of said one rabbet surface, means for detachably mounting said bar selectively on one of said die means, means on at least one of said first and second die means for supporting therebetween in a plane substantially normal to the planes of said plane surface and said plane face a metal sheet edge portion which measured from said plane surface to the adjacent sheet edge has a width substantially equal to said height, said bar when mounted in said rabbet cooperating upon said die member movement with said plane surface to bend said edge portion into an upstanding flange of said predetermined height and when mounted on said plane surface cooperating with said rabbet surfaces upon said die member movement to bend the portion of the sheet adjacent said edge portion to a position substantially normal to the edge portion and to the body of the sheet to provide the upstanding portion of a rebent flange having said edge portions as the outturned portion, two pairs of cutting elements selectively disposable on one of said die members positioned to have said sheet corner disposed adjacent thereto upon insertion of said sheet in the press, one of said pairs when disposed on said die member having the cutting elements thereof presenting a pair of rectangularly related plane surfaces each parallel to the direction of movement of the die members and extending in a plane parallel to the line of one of said adjacent edges and intersecting the line of the other edge, the projected planes of said plane surfaces defining on the sheet a square corner portion of an extent inward from each of said edges substantially equal to the combined height and width of said upstanding and outturned portions respectively of said rebent flange, the other of said pairs of cutting elements when disposed on said one die member having the cutting elements thereof presenting a pair of aligned plane surfaces extending diagonally relative to said adjacent sheet edges, the projected planes of said diagonal plane surfaces defining on the sheet a triangular corner portion of an extent along each of said edges substantially equal to twice said height, a pair of die blocks selectively securable on the other of said die members, one of said die blocks having a pair of rectangularly related plane surfaces each parallel to said direction of die member movement, said one die block being detachably securable on said other die member in a position with said plane surfaces thereof respectively in shearing relation with the plane surfaces of said one pair of cutting elements, the other die block having a plane surface parallel to said direction of movement and being detachably securable on said other die member in a position with said plane surfaces thereof respectively in shearing relation with the plane surfaces of said one pair of cutting elements, the other die block having a plane surface parallel to said direction of movement and being detach-

ably securable on said other die member in a position with said plane surface thereof extending diagonally relative to said adjacent edges in shearing relation with said diagonal plane surfaces of the other pair of cutting elements, means for detachably securing said cutting elements selectively on said one die member, and means for detachably securing the die blocks on said other die member selectively in said respective positions thereof, whereby preliminary to formation of rebent flanges on adjacent edges of the sheet the first cutting element pair may cooperate with said one die block to shear said square corner portion from the sheet, and prior to formation of upstanding flanges on said edges said other cutting element pair may cooperate with the other die block to shear said triangular corner portion from the sheet.

8. Structure substantially as defined in claim 7, in which each of the cutting elements of said one pair is spaced from said plane surface of the other cutting element thereof, and including a shear strip having a plane face flush with the plane surface of one of said cutting elements of the one pair and of appreciably less extent in said direction of movement and extending from said one element at least to the plane of said plane surface of said other cutting element.

9. In a press for cutting off corner portions of a sheet and cutting a substantially rectangular opening in the sheet in the forming of a panel from the sheet and having complementary die members relatively movable opposingly into engaged relation to effect said cutting of a sheet disposed therebetween, first shear die means on a first of said die members corresponding in outline to the opening to be cut, second shear die means on the second of said die members, said first and second shear die means being arranged for close-fitting telescoping movement to cut said sheet upon movement of the die members relatively toward each other, two pairs of cutting elements selectively mountable on one of the die members in position to have disposed adjacent thereto a sheet corner defined by adjacent edges of the sheet, one of said pairs when mounted on the die member having the cutting elements presenting a pair of rectangularly related cutting surfaces each parallel to the direction of movement of the die members and extending in a plane parallel to the line of one of said adjacent edges of the sheet and intersecting the line of the other edge, the projected planes of said surfaces defining on the sheet a square corner portion, the other pair of cutting elements when mounted on the die member having the cutting elements presenting a pair of aligned cutting surfaces extending diagonally relative to said sheet corner, the projected planes of said diagonal cutting surfaces defining on the sheet a triangular corner portion, a pair of cutting die blocks selectively securable on the other of said die members, one of said die blocks having a pair of rectangularly related plane surfaces each parallel to said direction of die member movement and extending transversely of one of said adjacent sheet edges, the other of said die blocks having a plane surface parallel to said direction of movement and extending diagonally relative to said adjacent sheet edges, said one die block being detachably securable on said other die member in position with said plane surfaces thereof respectively in shearing relation with the cutting surfaces of said one pair of cutting elements, said other die block being detachably securable on the other die member with said plane surface thereof in shearing relation with said diagonal plane surfaces of the other pair of cutting elements, means for detachably securing said die blocks selectively on said one die member, and means for detachably securing said die blocks selectively on said other die member.

of elements defining on the sheet a rectangular corner portion, and a third die block secured on said other die member having a pair of rectangularly related plane surfaces each parallel to said direction of movement and in 5 shearing relation with one of the cutting surfaces of the third pair of cutting elements.

10. In a press for cutting off corner portions of a sheet and cutting a substantially rectangular opening in the sheet in the forming of a panel from the sheet and having 10 complementary die members relatively movable opposingly into engaged relation to effect said cutting of a sheet disposed therebetween, first shear die means on a first of said die members corresponding in outline to the opening to be cut, second shear die means on the second 15 of said die members, said first and second shear die means being arranged for close-fitting telescoping movement to cut said sheet upon movement of the die members relatively toward each other, two pairs of cutting elements selectively mountable on one of the die members in position to have disposed adjacent thereto a sheet corner defined by adjacent edges of the sheet, one of said pairs when mounted on the die member having the cutting elements presenting a pair of rectangularly related cutting surfaces each parallel to the direction of movement of 20 the die members and extending in a plane parallel to the line of one of said adjacent edges of the sheet and intersecting the line of the other edge, the projected planes of said surfaces defining on the sheet a square corner portion, the other pair of cutting elements when mounted on the die member having the cutting elements presenting a pair of aligned cutting surfaces extending diagonally relative to said sheet corner, the projected planes of said 25 diagonal cutting surfaces defining on the sheet a triangular corner portion, a pair of cutting die blocks selectively securable on the other of said die members, one of said die blocks having a pair of rectangularly related plane surfaces each parallel to said direction of die member movement and extending transversely of one of said adjacent sheet edges, the other of said die blocks having a 30 plane surface parallel to said direction of movement and extending diagonally relative to said adjacent sheet edges, said one die block being detachably securable on said other die member in position with said plane surfaces thereof respectively in shearing relation with the plane surfaces of said one pair of cutting elements, said other die block being detachably securable on the other die member with said plane surface thereof in shearing relation with said diagonal plane surfaces of the other pair of cutting elements, means for detachably securing said 35 cutting elements selectively on said one die member, and means for detachably securing said die blocks selectively on said other die member.

11. Structure substantially as defined in claim 9, in which at least one of the cutting elements of said one pair and third pair is spaced from said plane surface of the other die element of the pair and includes a shear strip having a plane face flush with the plane surface of said one cutting element and of appreciably less extent in said direction of movement and extending from said 40 one element at least to the plane of the plane surface of the other cutting element of the pair.

12. In a press having complementary die members relatively movable opposingly into engaged relation for bending a marginal portion of a metal sheet to provide thereon either an upstanding flange of predetermined height or a rebent flange having an upstanding portion of substantially said height and an outturned portion extending from said upstanding portion a distance substantially equal to said height, first die means on one of said die 45 members having substantially parallel to the direction of said relative movement a plane surface of an extent in said direction at least equal to said height, second die means on the other die member having a first plane face parallel to the plane of said plane surface and spaced 50 therefrom by substantially the thickness of said sheet and

also having a second plane face normal to said first face, said second die means having therein a dihedral rabbet defined by a pair of rectangularly related surfaces each extending substantially parallel to one of said faces and having a width substantially equal to said height, a die bar of substantially square cross section each side of which has a width substantially equal to said height, said bar being selectively mounted on said second die means in said rabbet with two adjacent sides thereof substantially flush with the corresponding faces of said second die means or on said first die means projecting from the plane surface with one side substantially normal thereto and a side adjacent said one side parallel to the plane surface and spaced by substantially the thickness of said sheet from the plane of the rabbet surface parallel to said first face of the second die means, means for detachably mounting said bar selectively on one of said die means, and means on at least one of said first and second die means for supporting therebetween in a plane substantially normal to the planes of said plane surface and said first face a metal sheet edge portion which measured from said plane surface to the adjacent sheet edge has a width substantially equal to said height, said bar when mounted in said rabbet cooperating with said plane surface upon said die member movement to bend said edge portion into an upstanding flange of said predetermined height and when mounted on said plane surface cooperating with said rabbet-defining surfaces upon said die member movement to bend the portion of the sheet adjacent said edge portion to a position substantially normal to the edge portion and to the body of the sheet to provide the upstanding portion of a rebent flange having said edge portion as the outturned portion.

13. In a press having complementary die members relatively movable opposingly into engaged relation for bending a marginal portion of a metal sheet to provide thereon either an upstanding flange of predetermined height or a rebent flange having an upstanding portion of substantially said height and an outturned portion extending from said upstanding portion a distance substantially equal to said height, first die means on one of said die members having substantially parallel to the direction of said relative movement a plane surface of an extent in said direction at least equal to said height, second die means on the other die member having a plane face parallel to the plane of said plane surface and spaced therefrom by substantially the thickness of said sheet, a dihedral rabbet defined in said second die means by a pair of rectangularly related surfaces with one thereof extending substantially parallel to said face and each having a width substantially equal to said height, a die bar of a cross section providing two adjacent sides rectangularly related and corresponding in width to said rabbet surfaces and a third side parallel to one of said two sides, said bar being selectively mounted either on said second die means in said rabbet with said two adjacent sides thereof engaging on the rabbet surfaces and said third side substantially flush with said plane face of said second die means or on said first die means projecting from the plane surface with one of said two adjacent sides engaging thereon and the other substantially normal thereto and said third side disposed parallel to the plane surface and spaced by substantially the thickness of said sheet from the plane of the rabbet surface parallel to said plane face of the second die means, means for detachably mounting said bar selectively on one of said die means, and means on at least one of said first and second die means for supporting therebetween in a plane substantially normal to the planes of said plane surface and said first face a metal sheet edge portion which measured from said plane surface to the adjacent sheet edge has a width substantially equal to said height, said die bar when mounted in said rabbet cooperating with said plane surface upon said die member movement to bend said edge portion into an upstanding flange of said predetermined height and when mounted on said plane surface cooperating with said rabbet-defining surfaces upon said die member movement to bend the portion of the sheet adjacent said edge portion to a position substantially normal to the edge portion and to the body of the sheet to provide the upstanding portion of a rebent flange having said edge portion as the outturned portion.

mined height and when mounted on said plane surface cooperating with said rabbet-defining surfaces upon said die member movement to bend the portion of the sheet adjacent said edge portion to a position substantially normal to the edge portion and to the body of the sheet to provide the upstanding portion of a rebent flange having said edge portion as the outturned portion.

14. In a press for cutting a substantially rectangular opening in a metal sheet and having complementary opposed die carriers relatively movable perpendicularly of each other into engaged relation to effect said cutting, rectangular first die means on one of said die carriers corresponding in outline to the opening to be cut and affording support for a metal sheet inwardly from said outline, and second die means on the other of said die carriers rectangularly arranged to receive therewithin in close-fitting slidable relation said first die means whereby to cut said sheet upon relative engaging movement of the die carriers with said sheet therebetween, said second die means comprising four cutting elements each extending along one side of a rectangle corresponding to a side of the opening, each of said elements having a slightly curved cutting edge for cutting through the sheet with a progressive shearing action to define one side of the opening.
15. In a press for cutting a substantially rectangular opening in a metal sheet and having complementary opposed die carriers relatively movable perpendicularly of each other into engaged relation to effect said cutting, rectangular first die means on one of said die carriers corresponding in outline to the opening to be cut and affording support for a metal sheet inwardly from said outline, rectangular second die means on the other of said die carriers; said first and second die means being arranged to telescope in close-fitting slidable relation whereby to cut said sheet upon relative engaging movement of the die carriers with said sheet therebetween, at least one of said die means comprising four cutting elements each extending along one side of a rectangle corresponding to a side of the opening, and at least one of said elements having a slightly curved cutting edge for cutting through the sheet with a progressive shearing action to define one side of the opening.
16. In a press having complementary die members relatively movable opposingly into engaged relation for bending portions of adjacent edges of a rectangular metal sheet to provide thereon either upstanding flanges having inclined angled ends or rebent flanges each having an upstanding portion and an outturned portion, means for cutting off a corner of the sheet between said adjacent edges preliminarily to the forming of said flanges, said means comprising two pairs of die elements selectively disposable on one of said die members positioned to have said sheet corner disposed adjacent thereto upon insertion of said sheet in the press, one of said pairs when disposed on said one die member having the die elements thereof presenting a pair of rectangularly related plane surfaces each parallel to the direction of movement of the die members and extending in a plane parallel to the line of one of said adjacent edges and intersecting the line of the other adjacent edge, the projected planes of said plane surfaces defining on the sheet a rectangular corner portion of an extent inward from each of said edges substantially equal to the combined height and width of said upstanding and outturned portions respectively of said rebent flange, the other of said pairs of die elements when disposed on said one die member having the die elements thereof presenting a pair of aligned plane surfaces extending diagonally relative to said adjacent sheet edges, the projected planes of said diagonal plane surfaces defining on the sheet a triangular corner portion of an extent along each of said edges substantially equal to twice the height of said upstanding flanges, a die block on the other of said die members having a pair of rectangularly extending plane surfaces each parallel to said direction of die mem-

ber movement and of at least said corner portion extent, said die block being detachably securable on said other die member selectively either in one position with said plane surfaces thereof respectively in shearing relation with the plane surfaces of said one pair of die elements or in a second position with one of said plane surfaces thereof extending diagonally relative to said adjacent sheet edges in shearing relation with said diagonal plane surfaces of the die elements of said other pair, means for detachably securing said die elements on said one die member, and means for detachably securing the die block on said other die member selectively in one of said positions, whereby preliminary to formation of rebent flanges on adjacent edges of a sheet said surfaces of said one die element pair may cooperate with said die block surfaces to shear said rectangular corner portion from the sheet upon said relative die member movement with the die block secured in said first position, and preliminary to formation of upstanding flanges on adjacent sheet edges said surfaces of said other die element pair may cooperate with said one diagonally extending die block surface to shear said triangular corner portion from the sheet upon said relative die member movement with said die block secured in said second position thereof.

17. In a press having complementary die members relatively movable opposingly into engaged relation for bending portions of adjacent edges of a rectangular metal sheet to provide thereon either upstanding flanges having inclined angled ends or rebent flanges each having an upstanding portion and an outturned portion, means for cutting off a corner of the sheet between said adjacent edges preliminarily to the forming of said flanges, said means comprising two pairs of die elements selectively disposable on one of said die members positioned to have said sheet corner disposed adjacent thereto upon insertion of said sheet in the press, one of said pairs when disposed on said one die member presenting a pair of rectangularly related plane surfaces each parallel to the direction of movement of the die members and extending in a plane parallel to the line of one of said adjacent edges and intersecting the line of the other adjacent edge, the projected planes of said plane surfaces defining on the sheet a square corner portion of an extent inward from each of said edges substantially equal to the combined height and width of said upstanding and outturned portions respectively of said rebent flange, the other of said pairs of die elements when disposed on said one die member presenting a pair of aligned plane surfaces extending diagonally relative to said adjacent sheet edges, the projected planes of said diagonal plane surfaces defining on the sheet a triangular corner portion of an extent along each of said edges substantially equal to twice the height of said upstanding flanges, a pair of die blocks selectively securable on the other of said die members, one of said die blocks having a pair of rectangularly extending plane surfaces each parallel to said direction of die member movement and of at least said corner portion extent, said one die block being detachably securable on said other die member in a position with said plane surfaces thereof respectively in shearing relation with the rectangularly related plane surfaces of said one pair of die elements, the other of said die blocks having a plane surface parallel to said direction of movement and extending diagonally relative to said adjacent edges with the plane thereof defining with said edges a triangle corresponding to said triangular corner portion, said other die block being detachably securable on said other die member in a position with said diagonally extending surface thereof disposed in shearing relation with said diagonal plane surfaces of the die elements of said other pair, means for detachably securing said die elements on said one die member, and means for detachably securing the die blocks on said other die member selectively in the respective positions thereof, whereby preliminary to formation of rebent flanges on adjacent edges of a sheet said

surfaces of said one die element pair may cooperate with said surfaces of said one die block to shear said square corner portion from the sheet upon said relative die member movement, and preliminary to formation of upstanding flanges on adjacent sheet edges said diagonal surfaces of said other die element pair may cooperate with said diagonally extending surface of said other die block to shear said triangular corner portion from the sheet upon said relative die member movement.

18. Structure substantially as defined in claim 17, in which each of said die elements of said one pair is spaced from said plane surface of the other die element of the pair, and including a shear strip associated with each of said die elements of appreciably less extent in said direction of movement than said die elements and having a plane face flush with said plane surface of the associated die element and extending from the associated die element to the plane of said plane surface of the other die element.

19. In a press for forming sheets into assemblable panels of two differing complementary shapes each including an eccentrically located aperture and requiring relative reversal for assembly thereof and register of the apertures, die structure for forming both shapes of panels including alternative die parts for selective incorporation therein in accordance with the shape of panel to be formed, said die structure comprising a pair of die carriers relatively movable toward each other into engaged relation to form a sheet therebetween into a panel, first shear die means on one of said carriers located eccentrically of the panel and defining an outline corresponding to that of an aperture to be cut in the panel, second shear die means on the other carrier, said first and second shear die means being arranged for close-fitting telescoping cooperation to cut said aperture in the panel upon movement of the die carriers into engaged relation, a panel ejector member movable between and in the same plane as said die carriers for engagement with a formed panel to support such panel clear of the die carriers, said ejector member corresponding generally in dimensions and shape to the panel and having an opening located eccentrically thereof accommodating the shear die means therein, means for guiding the ejector member for movement in said plane including elongated means extending substantially normal to one face of the ejector member, means for detachably securing said elongated means selectively to either face of the ejector member to permit face-for-face reversal thereof for reversing the location of said opening relative to the center of the ejector member, and means removably attaching said shear die means to the respective die carriers within the outline of said opening selectively at said eccentric location or said reversed location thereof.

20. In a press for forming two assemblable panels of differing complementary shapes each including an eccentrically located formation and requiring relative reversal for assembly thereof and registration of said formation, die structure for forming both shapes of panels including alternative die parts for selective incorporation therein in accordance with the shape of panel to be formed, said die structure comprising a pair of die carriers relatively movable toward each other into engaged relation to form a panel therebetween, first and second die means respectively on one and the other of said carriers located eccentrically of the panel and arranged for telescoping cooperation to define said formation in the panel upon movement of the die carriers into engaged relation, a panel ejector member movable between and in the same plane as said die carriers for engagement with a formed panel to support such panel clear of the die carriers, said ejector member corresponding generally in dimensions and shape to the panel and having an opening located eccentrically thereof accommodating said die means therethrough, means for guiding the ejector member for movement in said plane including elongated means extending substantially normal to one face of the ejector member,

means for detachably securing said elongated means selectively to either face of the ejector member to permit face-for-face reversal thereof for reversing the location of said opening relative to the center of the ejector member, and means removably attaching said die means to the respective die carriers within the outline of said formation selectively at said eccentric location or said reversed location thereof.
